UNITED STATES PATENT OFFICE.

BERT G. HACKETT, OF PROVIDENCE, RHODE ISLAND, ASSIGNOR OF ONE-HALF TO
ARTHUR COOPERNAN, OF PROVIDENCE, RHODE ISLAND.

AIR-VALVE CAP.

1,403,406.

Specification of Letters Patent. Patented Jan. 10, 1922.

Application filed July 26, 1920. Serial No. 398,881.

To all whom it may concern:

Be it known that I, BERT G. HACKETT, a citizen of the United States, residing at Providence, in the county of Providence and 5 State of Rhode Island, have invented certain new and useful Improvements in Air-Valve Caps, of which the following is a specification.

This invention relates to an improvement 10 in air valve caps for use in closing the end of an air-valve casing employed in automobile tubes and other air cushions, and the object of this invention is the provision of such a cap having a closed neck portion and 15 a hollow body portion in which body an elastic packing ring is carried, the same having a central tubular non-yielding rivet or ferrule for limiting the inward expansion of the packing ring under pressure to positively prevent this packing from engaging 20 the valve stem and interfering with the closing of the valve when the cap is screwed into position.

The nature and advantages of the invention 25 will be better understood when the following detail description is taken in connection with the accompanying drawings, the invention residing in the combination and arrangement of parts as claimed.

30 In the drawings forming part of this specification, like numerals of reference indicate similar parts in the several views and wherein:—

Figure 1 is a longitudinal sectional view 35 illustrating my improved cap as applied to an air-valve casing.

Figure 2 is a section of the cap removed.

Figure 3 is an enlarged section of the 40 elastic packing which is carried in the body of the cap.

Figure 4 is a perspective view of the center non-yielding tubular rivet or ferrule.

Figure 5 is a top view of the packing ring.

It is found in practice that the elastic 45 packing carried by the usual valve cap, when compressed by the positioning of the cap upon its tube or casing often compresses slightly inwardly at its center thereby reducing its central or stem-receiving opening 50 so as to engage the valve stem, pressing it downward and opening the valve slightly causing a slow leak in the tire or air-tube to which the same is attached.

The following is a detail description of one construction of cap by which the above difficulties are obviated:—

With reference to the drawings, 10 designates the usual valve casing which is ordinarily applied to a pneumatic tire-tubing in which casing is mounted the usual air-valve 15 11 which is provided with an outwardly-extending stem portion 12.

It is found in practice necessary to provide a cap 13 to be screwed onto the outer end of this casing 10, to cover this valve- 65 stem 12 and protect the valve within.

To accomplish this in a simple and effective way without interfering with the action of the valve, I have provided such a cap with a hollow body portion 14 having an 70 internally threaded neck portion 15 which is slightly smaller in diameter than that of said body portion thereof thus providing an inner chamber 16.

The outer neck portion 17 of this cap is 75 closed or formed of solid stock so as to prevent the escape of air pressure therethrough.

In order to seal this cap when screwed into position on its casing, I have mounted a collar or ring 18 therein of compressible 80 material such as rubber or other suitable elastic material and in the center portion of this ring, I have inserted a hollow or tubular rivet or ferrule having an upper flange 19 on the top of the packing ring and a flange 85 20 on the lower portion of the packing ring and a hollow center portion 21 through which the stem 12 of the valve may extend.

By this construction it will be seen that when this cap is screwed onto the end of 90 the casing, as illustrated in Figure 1, this packing ring is engaged between the upper shoulder 22 in the hollow body of the cap and the end 23 of the casing, whereby this packing is squeezed between these two surfaces causing it to expand outwardly against the walls of the chamber rendering the threaded portion 23 tight against the leakage of air if any should escape through the valve and as the neck portion of the cap is 100 closed the cap is rendered air tight.

By the use of this means, for preventing the elastic ring from expanding inwardly, the full opening or space in the tubular rivet is maintained regardless of the amount of 105 pressure exerted upon the packing ring, and

therefore this packing ring cannot in any way engage the valve stem, to force the valve from its seat by the positioning of the cap.

The device is extremely simple and practical in construction and by its use the trouble heretofore experienced by slow leaks due to a slight opening of the valve by the positioning of the cap, is effectually prevented.

The foregoing description is directed 10 solely towards the construction illustrated, but I desire it to be understood that I reserve the privilege of resorting to all the mechanical changes to which the device is susceptible, the invention being defined and limited only 15 by the terms of the appended claims.

I claim:

1. A cap for air-valve casings having an air-tight outer end portion and a hollow body portion, an elastic packing ring carried 20 in said hollow body, and a non-yielding ring-shaped eyelet having flaring ends and set in the middle of said elastic ring to limit

its inward expansion under pressure whereby the valve stem may extend through said ring ferrule without danger of being engaged and pressed from its seat by the positioning of said cap. 25

2. A cap for air-valve casings having an air-tight outer end portion and a hollow body portion, an elastic packing ring carried 30 in said hollow body, and a non-yielding ring-shaped eyelet set in the middle of said elastic ring to limit its inward expansion under pressure whereby the valve stem may extend through said eyelet without danger 35 of being engaged and pressed from its seat by the positioning of said cap, the periphery of said packing fitting the inner wall of said hollow body whereby when compressed therein the escape of air past it will 40 be prevented.

In testimony whereof I affix my signature.

BERT G. HACKETT.
